Orville T. Stall, 7908 Chatfield Ave., Whittier, Calif.

Filed Mar. 23, 1962, Ser. No. 69,400

Term of patent 14 years

(Cl. D21—1)

FIG. 1 is an isometric view of a drapery glide embodying my new design;

FIG. 2 is a side elevational view;

FIG. 3 is an end elevational view, the end opposite that shown being substantially the same in appearance as the end shown;

FIG. 4 is a side elevational view showing the side opposite that shown in FIG. 2;

FIG. 5 is a top plan view;

FIG. 6 is a bottom plan view; and

FIG. 7 is a view similar to FIG. 3, showing one element of the design in another position.

I claim:

The ornamental design for a drapery glide, as shown and described.
